COMBINED SEAT AND EASEL

Raymond E. Cote, Menomonee, Wis.

Application July 26, 1954, Serial No. 31,600

Term of patent 14 years

(Cl. D15—8)

FIG. 1

FIG. 2

FIG. 3

FIG. 4

To all whom it may concern:

Be it known that I, Raymond E. Cote, have invented a new, original, and ornamental Design for Combined Seat and Easel, of which the following is a specification, reference being had to the accompanying drawing, forming a part hereof.

Fig. 1 is a front perspective view of a combined seat and easel showing my new design;

Fig. 2 is a side view of the design shown in Fig. 1;

Fig. 3 is a plan view of the design shown in Fig. 1; and

Fig. 4 is a right end view of the design shown in Fig. 1.

I claim:
The ornamental design for a combined seat and easel, as shown.
